UNITED STATES PATENT OFFICE.

WILLIAM O'NEILL, OF NEW YORK, N. Y., ASSIGNOR OF ONE-HALF TO SIMON MEYER, OF NEW YORK, N. Y.

BOTTLE-CAP REMOVER.

1,212,389.

Specification of Letters Patent. Patented Jan. 16, 1917.

Application filed October 9, 1916. Serial No. 124,454.

To all whom it may concern:

Be it known that I, WILLIAM O'NEILL, a citizen of the United States, residing at the city, county, and State of New York, have 5 invented certain new and useful Improvements in Bottle-Cap Removers, of which the following is a specification.

This invention relates to an improved device for removing bottle caps of the well 10 known crown type.

The objects of my invention are to provide a cap removing device of simple and inexpensive construction, which is adapted to be attached to the neck of a bottle and by 15 means of which the cap may readily be removed. I attain these objects as well as others not specifically stated by means of the device illustrated in the accompanying drawings in which,

20 Figure 1 is a side view of the device applied to the neck of a bottle, showing the parts in inoperative position. Fig. 2 is a front view of a modified form partly in section. Fig. 3 is a perspective view of 25 the device, showing the parts in position for removing the cap, and Fig. 4 is a front view of the device detached from the bottle.

Similar reference characters refer to similar parts throughout the several views.

30 The device consists generally of two parts, namely, an arm adapted to engage the rim of the cap and to raise it from the neck of the bottle, and a lever for operating the arm; each of said parts being 35 preferably made of a single piece of wire.

Referring to the drawing, in which I have shown a preferred embodiment of my invention, 1 designates the operating lever which is substantially U-shaped and formed 40 with a pair of oppositely disposed upright loops or eyes 2. The ends of the two side arms of the lever are bent inwardly to form fulcrums or lugs 3. The cross arm of the lever is preferably slightly concaved, as 45 shown in Fig. 2, to afford a finger hold.

The neck 4 of the bottle is provided with diametrically opposite recesses 5 forming sockets for the reception of the fulcrums 3 of the lever. While I prefer to attach the 50 lever directly to the bottle in the manner described, it will be understood that the lever might be fastened in other ways, as for example, a band provided with sockets

might be applied to the neck of the bottle. The lifting arm 6 is also bent in U-shape 55 and has its ends 7 outturned and engaged in the eyes 2 of the lever to form a hinge connection for the two parts. The upper bar of the arm 6 is preferably flattened and roughened on top to afford a good hold on 60 the rim of the cap.

The eyes 2 are arranged to press against the vertical members of the arm 6, as seen in Figs. 3 and 4, so as to spring the arm inward toward the neck of the bottle and 65 direct it upward against an edge of the cap upon upward movement of the lever whereby to lift the cap and remove it from its seat.

In the modified form of the device shown 70 in Fig. 2 one of the ends 7 of the lifting arm 6 is extended laterally and bent back over the lever 1 to form a spring-finger 8 by means of which the arm is pressed inward and upward upon operation of the 75 lever.

In removing a cap the neck of the bottle is grasped in the fingers and the lever is manipulated by movement of the thumb thus permitting of operation of the device 80 with one hand so as to leave the other free to hold a glass or for any other purpose.

It will be understood that the construction and arrangement of the various parts may be modified from those illustrated in 85 the accompanying drawing without departing from the scope of my invention.

What I claim is:

1. A bottle cap remover, comprising a lever adapted for attachment to the neck 90 of a bottle, a cap lifting arm hingedly connected to the lever, and means for pressing said arm inward upon upward movement of the lever.

2. A bottle cap remover, comprising a 95 lever having a pair of fulcrums adapted for engagement in sockets at opposite sides of a bottle-neck, a cap lifting arm hingedly connected to the lever, and means for pressing said arm inward upon upward movement of the lever.

3. A bottle cap remover comprising a substantially U-shaped lever having its side portions provided with oppositely disposed upright eyes and having its ends inturned, 105 and a substantially inverted U-shaped lift-

ing arm having its ends outturned and engaged in said eyes, one of the ends of said arm being extended laterally and bent back over the lever.

5 4. The combination of a bottle-neck having diametrically opposite sockets, a lever having a pair of fulcrums engaged in said

sockets, a cap-lifting arm hingedly connected to the lever, and means for pressing said arm inward upon upward movement 10 of the lever whereby to engage an edge of the cap and remove it from the bottle.

WILLIAM O'NEILL.
